SALAD SERVER OR THE LIKE

Vance E. Dimmick, 9 Benedict Court, Norwalk, Conn.

Filed Mar. 22, 1965, Ser. No. 84,388

Term of patent 14 years

(Cl. D44—29)

FIG. 1 is a top plan view of a salad server or the like showing my new design;

FIG. 2 is a bottom plan view;

FIG. 3 is a sectional view on line 3—3 of FIG. 2;

FIG. 4 is a sectional view on line 4—4 of FIG. 1;

FIG. 5 is a top plan view of another embodiment of my design for a salad server or the like wherein the obverse face is oppositely oriented from that shown in FIG. 1, and wherein the bowl is provided with slots so as to form tines therein;

FIG. 6 is a bottom plan view thereof;

FIG. 7 is a sectional view on line 7—7 of FIG. 5; and

FIG. 8 is a sectional view on line 8—8 of FIG. 5.

I claim:

The ornamental design for salad server or the like, substantially as shown and described.
